UNITED STATES PATENT OFFICE.

JOSEPH N. PAUL, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed July 7, 1919. Serial No. 309,068.

To all whom it may concern:

Be it known that I, JOSEPH N. PAUL, a citizen of the United States, and resident of the city of Rochester, in the county of Monroe and State of New York, have invented a new and useful Automatic Train-Control System, of which the following is a specification.

This invention relates to automatic train control systems for railways, and more particularly to a means for transmitting controlling impulses or influences from the trackway to moving locomotives, motor cars or other railway vehicles, by electromagnetic induction, and without physical contact between any parts on the vehicles and parts along the track.

One object of my invention is to improve the operating characteristics of impulse transmitting means of the electromagnetic type, so that the car-carried and the trackway impulse devices may be made more sensitive and reliable in their performance, may be reduced in size, and can be made so as not to be improperly affected by track rails, or other magnetic bodies along the track.

A further object is to provide an impulse transmitting means employing electro-magnetic induction which will be accurately responsive to the speed at which the vehicle passes the control points, and which can be rendered capable of acting at various selected speeds by constructing or adjusting either the trackway element or the car equipment. For instance, my invention enables the desired impulse to be transmitted to a vehicle at any speed thereof above a predetermined minimum.

A still further object is to provide impulse transmitting means of the inductive type in which the impulse received on the vehicle will be prolonged or drawn out, so to speak, so that effective and reliable operation of an ordinary relay may be obtained, without employing large or expensive trackway elements.

Generally stated, I attained these and other objects by utilizing the special electrical characteristics of an amplifying and detecting relay device of the thermionic or vacuum bulb type, commonly known as an audion.

Other objects and specific features of my

invention will appear more fully herein- 55 after as the description progresses.

In describing my invention in detail I will refer to the accompanying drawing, in which are illustrated various embodiments of the invention, in which like reference 60 characters refer to corresponding parts in the several views, and in which:

Figure 1 shows diagrammatically one arrangement of trackway circuits which may be employed in connection with the impulse 65 transmitting means embodying my invention; Fig. 2 illustrates in a diagrammatic and simplified manner the construction and arrangement of the parts constituting the car equipment, together with the trackway 70 element; Fig. 3 is a curve illustrating a typical operating characteristic of audions which is utilized in my invention; Fig. 4 shows a modified construction and arrangement of the car equipment; Fig. 5 is another 75 curve of a characteristic of audions which illustrates the effect of cooling the filament upon the current in the plate circuit; Figs. 6 to 8 illustrate modifications of connections and arrangements of batteries for the car 80 equipment; Fig. 9 illustrates a modified construction in which a permanent magnet is used for the trackway element; and Figs. 10 to 15 show further modifications of the 85 car equipment.

The impulse transmitting means embodying my invention includes trackway elements which are governed in accordance with traffic conditions. Various arrangements of trackway circuits for governing 90 these trackway elements may be employed; and the trackway circuits illustrated in Fig. 1 are merely typical. Referring to Fig. 1, the track rails 1 of the railroad track are divided by insulated joints 2 into blocks 95 in the usual way, one block I with the adjacent ends of two other blocks H and J being shown. The parts and circuits associated with the various blocks are the same, and for convenience will be given like reference characters, with distinctive exponents. Each of the blocks is provided with a track battery 3 and a track relay 4, the same as in ordinary block signal systems. My invention may be used with or without the usual fixed signals, depending upon the type of train control apparatus; and I have illustrated such fixed signals S conventionally,

without attempting to illustrate their well known control circuits and devices.

The trackway element T of my invention in general comprises a magnetic yoke or core and associated coils, and is adapted to influence by electro-magnetic induction a co-operating element on a passing vehicle. In the construction illustrated, the trackway element T comprises a U-shaped core or yoke 5 provided with pole pieces 6, and having coils 7 on its legs which are either oppositely wound or are wound in the same direction with different number of turns. These trackway elements T are intended 10 to transmit controlling influences or impulses to a passing train at one or more control points in each block, in accordance with traffic conditions in the next block in advance alone, or both the next block in advance and the corresponding block, depending upon the type of train control apparatus employed. In the trackway equipment shown in Fig. 1, a trackway element T is located at the entrance to each block, a 15 short distance in the rear of the insulated joints 2, the normal direction of traffic being from left to right, as indicated by the arrow. The coils 7 of each trackway element T are connected in series in a normally closed circuit including the front contact of a line relay 8. In the arrangement illustrated, the controlling circuit for the line relay 8 includes a front contact of the track relay 4 of the corresponding block and a front contact of the track relay 4 of the next block in advance, so that the coils 7 of the trackway element T at the entrance to each block are short-circuited under clear traffic conditions, but are open-circuited when either 20 the corresponding block or the next block in advance is occupied. The trackway elements T may be located crosswise of the track between the track rails (as shown in Fig. 1), or lengthwise, or outside of either 25 track rail, as preferred.

I prefer in practice to have the upper faces of the pole pieces 6 of the trackway element T as high as clearances on the particular railroad equipped will permit; and in some instances I consider it desirable to 30 locate the trackway elements outside of the track rails, since there is more vertical clearance space ordinarily available outside of track rails than between them. It should 35 be understood that other arrangements and constructions of trackway elements may be employed, without departing from the essential features of my invention.

The car-carried element L for cooperating 40 with the trackway element T, comprises in general an inverted U-shaped magnetic core or yoke, provided with pole pieces, and having coils on its legs. This car-carried element L is supported in any suitable manner 45 from the frame of the locomotive or other

vehicle, and is positioned thereon so that its pole pieces pass directly over the pole pieces 6 of the trackway element T, as shown in Fig. 2. The thermionic relay device or audion, employed in my invention, being well known, has been illustrated conventionally. This audion comprises a filament F, a grid G and a plate P. This audion is connected in circuit with suitable sources of current, the coils of the car-carried element 75 L, and a control relay R, in any one of the various ways hereinafter described, so as to govern the operation of said control relay R in accordance with traffic conditions. The control relay R may be of any suitable type, 80 but according to my investigations to date, I prefer a relay of the tractive type which is provided with a large number of turns so as to be operable on small currents, and which has a laminated core, in order to be 85 quick-acting.

The control relay R may govern the operation of any suitable form of train control apparatus or device. Since the particular type of train control apparatus forms no part of my invention, I have illustrated such device K conventionally as an electro-pneumatic valve, which may vent the train pipe and apply the brakes directly, or govern the operation of any other suitable form of train control means. The train control device K is normally energized when the control relay R is picked up and is de-energized when the said control relay drops. In the construction illustrated, the dropping of the control relay R is only momentary, so that the train control device K, if continued operation thereof is required, must be provided with a stick circuit or other equivalent means, such as disclosed, for example, in the application of Winthrop K. Howe, Serial No. 287,182, filed March 3, 1919, so that it will continue in operation after the control relay has picked up, so that, when once set into operation, it will continue in operation after the control relay has picked up until restored manually or otherwise. Obviously, however, the control relay R may be a stick relay or may be provided with equivalent means.

Referring first to the arrangement shown in Fig. 2, the coils 10 and 11 of the car-carried element L, which are oppositely wound, are connected in series in the grid circuit of the audion, which includes a battery C. The filament F is heated in the usual way by a battery A. The control relay R is included in the plate circuit of the audion, and is normally energized from a battery B. The voltages of the batteries are selected or adjusted so that normally, while the car-carried element L is not passing over the trackway element T, sufficient current flows in the plate circuit through the control relay R to close its contacts and

maintain the train control device K energized. For this purpose, I prefer to use a much lower voltage for the battery B in the plate circuit, than I understand has 5 heretofore been ordinarily employed with audions in radio work, and the potential on the grid produced by the battery C is, I believe, higher than that ordinarily obtained in radio work. The voltages of the batteries A, B and C will, of course, vary in practice, according to the type and operating characteristics of the audion, the control relay, and the electrical and magnetic 10 characteristics of the trackway and car-carried elements. One typical arrangement, which I found satisfactory in practice, consists of the battery A, 4 volts, battery B, 24 volts, battery C, 24 volts; but other combinations of batteries may be also used with 15 satisfactory results.

The operation of the system shown in Fig. 2 will now be briefly described. Normally the current in the grid circuit through the coils 10 and 11 produces a magneto-motive force sending flux through the yoke 9 of the car-carried element and through leakage paths around said yoke. In practice, with type of audion I have investigated, this current is comparatively small, and the 20 coils 10 and 11 must be wound accordingly. Under clear traffic conditions, the coils 7 of the trackway element T are short-circuited; and when the car-carried element L passes over the trackway element T in this 25 safe controlling condition, the car equipment is not influenced sufficiently to cause operation of the control relay R. I attribute this to the action of the short-circuited coils 7 of the trackway element T, which I believe choke back or oppose the passage of 30 flux through the yoke 5 of the trackway element, thereby preventing any considerable change of flux through the coils 10 and 11 of the car-carried element L. Under dangerous 35 traffic conditions, the coils 7 of the trackway element T are open-circuited, so that the trackway element presents in effect a dead magnetic loop to the car-carried element L on a passing vehicle. Thus, as the 40 car-carried element L approaches and comes directly over the trackway element T in this stopping condition, the reluctance of the magnetic circuit through the coils 10 and 11 is greatly reduced, and the flux through the 45 coils 10 and 11, due to the magneto-motive force produced by the current normally flowing in these coils, is increased. This increase in flux induces a counter E. M. F. in the coils 10 and 11, which, in accordance 50 with well known laws, opposes the battery C, and reduces the potential of the grid G with respect to the potential of the filament F. The normal potential on the grid G being reduced, the current normally flowing 55 in the plate circuit through the control re-

lay R is likewise reduced, due to the well known characteristic of the audion. The parts are proportioned and adjusted so that the current in the plate circuit is reduced in this way below the holdup value of the 60 control relay R, so that its contacts open and de-energize the train control device K, thereby placing the vehicle or train under the influence of the train control device K. As the car-carried element L passes away 65 from the trackway element T, the reluctance of the magnetic circuit through coils 10 and 11 is increased and the flux through these coils is consequently decreased. This decrease of flux induces an E. M. F. in coils 70 10 and 11 which aids the battery potential and so increases the positive potential of the grid G with respect to the potential of the filament F. This increase of normal grid potential will produce an increase in the 75 current flowing in the plate circuit through the control relay R. Although this increase of current in the control relay R may cause its contacts to close, the train control device K, being provided with a stick circuit or other equivalent means, will remain in operation until restored manually or otherwise, as previously explained. This is my understanding of why the control relay R drops under the conditions described, but 80 other factors may be involved in the operation.

One important requisite of train control systems is that failure of any of the essential parts likely to break down in practice should be upon the side of safety. In the arrangement shown in Fig. 2, it will be observed that interruption of the circuit through the train control device K will set 85 this device into operation. Likewise, interruption of the plate circuit, or depreciation of the battery B, will de-energize the control relay R, and thus set the train control device K into operation. Also, breaking 90 of the filament F, or depreciation of the battery A, reduces the current in the plate circuit and causes the control relay K to open. If the battery C depreciates, or any part of the grid circuit opens, the current 95 in the plate circuit through the control relay R is reduced below the holdup value of said relay.

Fig. 3 illustrates a typical curve between plate current as ordinates and grid voltage as abscissa, the plate voltage being maintained constant. From this curve it will be observed that increase in grid voltage produces an increase in the plate current, until a certain value of grid voltage is reached, whereupon further increase in grid voltage 100 reduces the plate current at first and then, when the grid voltage is carried to still higher values, there is little change in the plate current. In other words, this curve 105 has a knee or bend in it. The audion in my 110

invention may be satisfactorily worked at any grid voltage below the knee of the curve; but I prefer to work at a high grid voltage beyond the knee of the curve as indicated, for example, at a point *a*. By working at this point *a*, a small decrease in grid voltage does not greatly reduce the plate current, in fact, increasing it first. This arrangement has the advantage of making the apparatus stable and not too sensitive for practical use, since the voltages of the batteries may vary within the limits ordinarily occurring in practice, without causing a premature or improper operation 15 of the control relay.

Also, by working the audion at a grid voltage above the knee of the curve, I am able to employ that desirable type of track-way elements which, in the active or stopping condition, is in effect an inert mass of iron, and at the same time I can obviate improper operation of the apparatus by the track rails at switches, crossover and other complicated track layouts, and also by other 20 bodies of iron along the track, which may have a tendency to transmit a stopping impulse to a passing train in the same way as a trackway element. The influence of track rails and other foreign magnetic objects 25 along the track upon the car-carried element, is much less than that obtained from a trackway element, because the size and position of the track rails, and the like, does not make them as efficient a magnetic circuit. Consequently, the effect of the track rails upon 30 the grid voltage is only a fraction of the effect produced by an active trackway element, that is, one having its coils open-circuited; and by properly proportioning and 35 adjusting the parts and batteries, I find that the apparatus may be worked at such a grid voltage that the influence of track rails and other magnetic bodies ordinarily 40 encountered along a railway track, will cause little, if any, decrease in the plate current, and will not, therefore, drop the control relay. This particular feature of my 45 invention is, of course, only necessary with impulse devices of the type in which the 50 trackway element, when in the danger or stopping condition, merely constitutes a partial magnetic circuit.

In the modification of the car equipment illustrated in Fig. 4, two separate coils 12 and 13, connected in different circuits, are carried on the legs of the car-carried element *L*. One of these coils 12, which I term the field or primary coil, is connected in series with the filament *F* and battery *A*, 55 and supplies the greater part of magneto-motive force for producing flux in the yoke 9 of the car-carried element. The other coil 13, which I term the inducing or secondary coil, is connected in the grid circuit and 60 sup-plies some of the magneto-motive-force.

The modified arrangement of Fig. 4 has several advantages. The operation is in general similar to that already described in connection with Fig. 2. The potential induced in the secondary coil 13 by the track-way element lowers the potential of the grid *G*, in the same way as previously explained, to decrease the plate current. Also, for the same reasons, a counter E. M. F. is induced in the field coil 12 in opposition to the battery *A*. This momentarily reduces the voltage on the filament *F* and has the effect of partially cooling the filament. The effect produced upon the plate current by cooling the filament is illustrated by the curve in Fig. 5, which shows plate current plotted as ordinates against filament current as abscissa, the plate voltage and grid voltage being constant. From an inspection of this curve, it will be noted that a decrease in the filament current from any selected working value causes an amplified decrease in the plate current. In other words, the counter E. M. F. induced in the field coil 12 of the car-carried element *L* also tends to drop the control relay *R*, due to the cooling of the filament. According to my investigations to date, I prefer to work the filament current at or just above the knee or bend in this curve, as indicated at the point *b*, for the same reasons described, that is, in order to make the apparatus sufficiently stable for practical use and immune to the influence of track rails or the like. If desired, however, either or both the grid voltage or the filament current may be worked at high values; and in all cases the value of the filament current and grid voltage to be used in practice for the most effective results will depend largely upon the type and characteristics of the audion, and also the magnetic and electrical characteristics of the various parts of the car equipment and the trackway element, so that no arbitrary values can be assigned.

This cooling of the filament, characteristic of the arrangement of Fig. 4, also has the advantage of prolonging or dragging out, so to speak, the change in the plate current, perhaps because it takes an appreciable time for the filament to resume its normal working temperature, after having once been cooled. This prolonged change in the plate current produces a de-energizing influence upon the control relay *R* of sufficient duration to cause reliable operation thereof, even though the car-carried element passes very quickly over the trackway element, and even though the pole pieces of these respective elements are comparatively short. This permits the use of comparatively inexpensive and simple trackway elements and car-carried elements, and also obviates any need for extreme quick action on the part of the control relay.

Further regarding the arrangement shown

in Fig. 4, I have found that the most efficient results are obtained when the field coil 12 and the secondary coil 13 of the car-carried element L are wound in the proper direction and connected to the batteries A and C, so that the effect of reducing the potential of the grid by the E. M. F. induced in the secondary coil 13, and the effect of cooling the filament by the E. M. F. induced in the field coil 12, will be cumulative and not opposing each other. This arrangement, however, is not compulsory and may be modified to suit varying requirements.

Another feature of the arrangement illustrated in Fig. 4 is that the primary or field coil 12 is connected in series with the filament. Thus, if the circuit through the field coil 12 should break, the filament will cool and the control relay will drop, thereby detecting the failure. Also, if a cross occurs so as to short-circuit the field coil 12, the voltage applied to the filament F is greatly increased, due to cutting out the voltage drop through the field coil 12. By properly selecting the resistances and voltages, this increase in voltage due to short-circuiting the field coil 12 may be so great as to burn out the filament F, which will also cause the control relay R to drop. Moreover, if the field coil 12 is shunted out, the average potential of the filament F with respect to the grid G is increased, thereby in turn decreasing the plate current and causing the control relay R to drop. To explain more fully, assume the battery A to be 12 volts, and that there is an 8 volt drop in the field coil 12. Then, there are 4 volts across the filament F, and the average potential of the filament is two volts higher than its negative end which is connected to the grid circuit. If, now, a cross occurs to shunt out the field coil 12, the full voltage of the battery A is applied to the filament, increasing its average potential to six volts above its negative end, or four volts greater than the normal difference in potential between the grid and the filament. This is equivalent to reducing the grid potential with respect to the filament, and this causes the control relay to drop. These voltages are merely selected for purposes of illustration, and are subject to variation in practice. The protection against failure of the other circuits is the same as previously described, and likewise the modification of Fig. 4 may be selected and proportioned so as not to be improperly influenced by track rails or the like.

Fig. 6 illustrates a modification of the arrangement shown in Fig. 4. In this modification provision is made to detect and guard the apparatus against a cross short-circuiting the inducing or secondary coil. This is accomplished by employing a detecting device responsive to the flux which is produced by the secondary coil 13, so that,

unless said coil is connected properly in the grid circuit and is energized by the battery C, the detecting device will operate. In the simplified construction illustrated, this magnetic detector comprises an armature 15 which is pivotally supported at its lower end on the pole piece below the coil 13, and which is normally attracted by the flux produced by said coil against a residual pin of a projection 16 from the leg of the yoke 9 above said coil. This armature 15 is biased to the open position by a spring 17 and carries an insulated contact piece 18 adapted to make contact with suitable fixed contacts (indicated conventionally as arrows), which are included in the circuit for the train control device K. It will be evident that so long as flux is produced in the yoke 9, some of it will pass through the armature 15 and maintain it closed. This flux in the yoke 9 is produced partly by the field coil 12 and partly by the secondary coil 13; and the armature 15 may be designed and adjusted so that it will be attracted so long as both of these coils 12 and 13 are fully and properly energized, but will be pulled away by the spring 17 and set the train control device K into operation, whenever current ceases to flow through either or both of these coils 12 and 13. For example, assuming the coils 12 and 13 to have equal ampere turns, the armature 15 should be adjusted so as to pull away upon a reduction of approximately one-half in the flux normally passing through it. In this connection it should be noted that not all of the flux produced by the field coil 12 will pass through the righthand leg of the yoke 9, some of this flux being diverted to leakage paths; and consequently, even if the ampere turns of the coils 12 and 13 are equal, the coil 13 will predominate in its influence upon the armature 15. Obviously, the armature 15 may be associated with any part of the magnetic circuit through the coils 12 and 13; and the same armature may be used to detect failure of current through either coil, or separate armatures may be used for detecting failure of the current through the coils individually. Since failure of current through the field coil 12 is automatically detected by virtue of its connection into the filament circuit, as previously explained, I prefer in most instances the arrangement illustrated in Fig. 6, where the armature 15 is primarily under the influence of the secondary coil 13. The contacts 18 controlled by the armature 15 may be included in any one of the other circuits of the equipment, the interruption of which results in operating the train control device K.

Fig. 7 illustrates a modified arrangement of circuits in which the batteries A and C of Fig. 4 are combined in a single battery.

Fig. 8 illustrates a similar arrangement,

in which the batteries A and C are combined, and in which the difference of potential between the filament F and the grid G is produced by the voltage drop through the filament F.

Fig. 9 illustrates a modified construction in which a permanent magnet is employed with the trackway element, the car equipment illustrated being the same as that shown in Fig. 2. In this construction, the trackway element comprises a U-shaped permanent magnet 20 provided with the usual pole pieces 21 and having projections 22 affording leakage paths. The coils 23 on the legs of this permanent magnet 20 are placed between the pole pieces 21 and the projections 22; and these coils are energized from a battery 24 under clear traffic conditions, that is, when the line relay 8 is picked up. The coils 23 are so wound and connected with the battery 24 that the magneto-motive force produced thereby opposes that of the permanent magnet 20, thereby diverting the greater portion of the permanent flux through the leakage paths, so that the magnetic field above the pole pieces 21 of the trackway element T¹ is very weak. Under dangerous traffic conditions, the coils 23 are open-circuited, so that the full strength of the magnetic field of the permanent magnet 20 appears above the pole pieces 21 and embraces the yoke 9 on a passing car. Change of flux through the yoke 9 of the car-carried element induces an E. M. F. in the coils 10 and 11, and these coils are so wound, that the E. M. F. induced therein reduces the grid potential, thereby causing operation of the control relay R in the same way as previously explained. The battery C illustrated in Fig. 9 in the grid circuit is employed to maintain normally a difference of potential between the filament and the grid.

Fig. 10 illustrates an arrangement employing only the filament F and plate P of the audion, and operating by virtue of the effect produced on the plate current by cooling the filament F. In this arrangement, the filament F is connected in series with the two coils 10 and 11 on the legs of the car-carried element. Normally, the temperature of the filament, and the voltage in the plate circuit, are such as to permit sufficient current in the plate circuit to maintain the control relay energized. When the car-carried element passes over an active trackway element, the counter E. M. F. induced in the coils 10 and 11 opposes the battery C and cools the filament F to the point where the current in the plate circuit is decreased below the holdup value of the control relay R.

Fig. 11 illustrates a still further modification in which the field coil 12 of the car-carried element is energized from a battery 25 wholly disconnected from the audion or other devices. An armature 15¹, similar to

that shown in Fig. 6, previously described, is preferably employed in connection with the field coil 12 to detect any failure thereof. If desired, the secondary coil 13 may be provided with a similar detecting armature. In other respects this arrangement operates in the same manner as previously described.

Fig. 12 illustrates an arrangement in which a permanent magnet 26 is used on the car to produce the flux which is changed as the car passes over an active trackway element of the type shown in Fig. 2. The coils 10 and 11 on the legs of the permanent magnet 26 are connected in the grid circuit in the arrangement illustrated, the same as shown in Fig. 2; but any of the other various connections previously described may be employed, if desired, the permanent magnet constituting merely a substitute source of magneto-motive force, or an additional source, as the case may be, for producing the change of flux in the secondary coil of the car-carried element. The car equipment of Fig. 12 may also be used with the trackway element shown in Fig. 9, if desired, the polarity of the respective permanent magnets on the car and on the track being arranged such that these magnets act together to send flux through the secondary coils 10 and 11.

Fig. 13 illustrates an arrangement of circuits, similar to that shown in Fig. 4, in which a single battery, or strictly speaking, two sections 27 and 28 of a battery, are employed for the filament, grid and plate circuits. The operation of this modification, together with its features of protection, are the same as already described. The two sections 27 and 28 of the battery constitute the batteries B and C of Fig. 4, and the section 28 constitutes the battery A of Fig. 4. The energy demands upon these two sections are, according to my investigations, different and the number of cells included in these sections may be selected according to the energy demands. I prefer, however, to employ two sections of battery of the same voltage and capacity, and employ a change-over switch M, as shown in Fig. 14, so that these sections 27 and 28 may be used alternately in the filament circuit. The winding of the field coil 12 can be proportioned so that the same battery may be used in the filament circuit, instead of a section of battery, thereby energizing all circuits from the same battery.

Fig. 15 shows one construction of car equipment in which alternating current is employed instead of direct current obtained from batteries. This alternating current may be obtained on the car from any suitable source, as a motor generator driven from storage batteries, or, in the case of a locomotive, from a steam driven generator, such as is now commonly used to generate current for head-lights. I use a transformer 30

in the usual manner to obtain the desired voltages for the several circuits of the audion. In the arrangement shown, the filament F of the audion and the primary or field coil 12 of the car-carried element are connected in series. On account of the comparatively high impedance of the field coil 12, the voltage for the filament circuit will be several times higher than when direct current is used. The grid voltage is shown as obtained by transformer action between the field coil 12 and the secondary coil 13. The plate circuit is connected in the same way as previously described.

15 The operation of this modification is substantially the same as previously explained. The alternating current, being derived from the same source, will change polarity at the same instant in the various circuits, so that 20 the relative potentials in these circuits at every instant will be the same as if batteries were used. One important feature of this construction is the fact that failure of the secondary coil 13, as well as the field coil 12, is 25 automatically detected. The E. M. F. in the grid circuit including the secondary coil 13 is derived by transformer action, and consequently, if the secondary coil is open-circuited, or short-circuited by a break or cross, 30 the grid voltage decreases or falls to zero thereby causing the control relay to open.

One important characteristic of my invention is the fact that the apparatus may be proportioned or adjusted so that the control 35 relay will be operated when the car passes a trackway element in the danger position at any speed above a selected minimum. In other words, the effect of transmission of the impulse in accordance with my invention is 40 accurately dependent upon the speed of the car. I attribute this to the fact that the audion is essentially a device responding to voltage or potential changes more than to current changes. The voltage induced in a 45 coil on a car while passing over a trackway element, whether the flux is transmitted from the trackway or from the car, is theoretically, I believe, almost exactly in proportion to the speed of the car, and investigations indicate 50 that this is substantially true. However, when it is attempted to detect this induced voltage by the operation of a relay connected to the coil, it is found that, for some reason, perhaps on account of the inductance of 55 the coil and its associated relay, the current produced in the relay, while dependent to some extent upon speed, does not vary through wide enough limits, or accurately enough, to make the relay reliably responsive 60 according to different speeds of the car. According to my invention, however, the car equipment may be made responsive to speed within as narrow limits as desired; and without undue refinement, may be made to 65 act within a range of one or two miles per

hour at any speed above any desired or fixed minimum.

The limiting minimum speed at which the control relay R in my invention will operate, is dependent upon a number of factors, 70 any one of which may be used as a basis for varying this critical speed. An audion of different characteristics, a change in the voltages of the several batteries, variation 75 in the operating characteristics of the control relay, change in the air gaps between the car-carried element and the trackway element, a change in the amount and disposition of the windings of the coils of the car-carried element, a change in the size or cross 80 section of the car-carried element or trackway element, all vary to a more or less degree the critical limiting speed at which the control relay will drop. Any one of these 85 various factors may be modified, either on the track or on the train, to apply the impulse transmitting means embodying my invention to a system of speed control for trains, that is, a system in which the speed 90 of vehicles is regulated in accordance with traffic conditions in a predetermined manner.

In describing the invention, I have outlined some of the forms which the car equipment and trackway equipment may take but it should be understood that the modifications illustrated do not exhaust all of the various embodiments of my invention. Various types of car-carried and trackway 100 elements may be employed in my invention, the only essential requisite being that these elements shall cooperate to produce an induced voltage on the car by electro-magnetic induction from the trackway under 105 dangerous traffic conditions, and not under clear traffic conditions. Obviously, this essential requirement may be satisfied in various ways, some of which have been illustrated. The electro-motive force causing 110 the change of flux in the coil or winding on the car may be derived from a source on the car, as in Fig. 4, for example, or from a source on the track, as in Fig. 9 for example. I prefer a trackway element of 115 the type shown in Fig. 2 because of its simplicity and cheapness; and while a battery or other source of current on the track may be used in the circuit for the coil 7 to produce a magneto-motive force opposing that of the car-carried element and thus provide 120 the proceed indication, I prefer the arrangement illustrated, because it obviates the complications incident to the use of trackway batteries, and also the cost of their care and maintenance.

Furthermore, various modifications and adaptations of the audion and its connections to the coils of the car-carried element, other than those illustrated, may be employed without departing from my inven- 125 130

tion. For example, two or more audions, coupled in cascade, may be employed, if desired. Various connections of batteries or other sources of current to the coils and the elements of the audion may be used, provided the appropriate potentials upon the filament, grid and plate of the audion are obtained. For example, referring to Fig. 2, the voltage of the battery A is shown as adding to the voltages of the batteries B and C, but the connections may be arranged so that the battery A opposes either or both of the batteries B and C.

I desire to have it understood, therefore, that the specific embodiments of my invention shown and described are merely illustrative, and do not exhaust the modifications of the idea of means and the functions thereof constituting my invention.

20 What I claim as new and desire to secure by Letters Patent of the United States, is:

1. Impulse transmitting means for automatic train control systems comprising a trackway element having its magnetic condition governed in accordance with traffic conditions in advance, a car-carried element including a coil and adapted to cooperate with said trackway element to cause voltage to be induced in said coil under dangerous traffic conditions, train control means on the car, and a thermionic relay responsive to the voltage induced in said coil for governing said train control means.

2. In an automatic train control system for railroads having tracks divided into blocks each provided with a normally closed track circuit, a trackway element associated with each block and having its magnetic condition controlled by the track relay of the block next in advance, a car-carried element cooperating electro-magnetically with said trackway element, train control means on a car, and a thermionic relay on the car responsive to the cooperation of the car-carried element with a trackway element for governing said train control means.

3. In an automatic train control system, impulse transmitting means comprising, a car-carried element including a coil, trackway elements adapted when in the active stopping condition to cause voltage to be induced in said coil, and an audion for detecting said induced voltage.

4. In an automatic train control system, a car-carried circuit, traffic controlled means partly on the car and partly on the track for causing voltage to be induced in said circuit under dangerous traffic conditions, train control means on the car, and a thermionic relay responsive to the voltage induced in said circuit for governing the operation of said train control means.

5. In an automatic train control system, means for communicating electromagnetic

impulses or influences between the trackway 65 and moving vehicles comprising a car-carried circuit, means partly on the vehicle and partly along the track for causing voltage variations in said circuit, and means including an audion for detecting said voltage 70 variations, said audion being normally worked at a relatively high grid voltage.

6. In an automatic train control system, means for communicating electromagnetic impulses or influences between the trackway 75 and moving vehicles comprising a car-carried circuit, means partly on the vehicle and partly along the track for causing voltage variations in said circuit, an audion having its grid potential modified by the voltage 80 variations in said car-carried circuit, and a relay included in the plate circuit of the audion, the constants of said audion and the voltages used therewith being of such values that a small change in grid potential 85 will produce no change in plate current while a larger change in grid potential will cause a large change in plate current.

7. In an automatic train control system, means for establishing communication between the trackway and moving vehicles, comprising an audion on the vehicle, electro-responsive means included in the plate circuit of the audion, and traffic controlled means partly on the vehicle and partly along 95 the track for varying the temperature of the filament of said audion.

8. Impulse transmitting means for automatic train control systems comprising, in combination, a coil on the vehicle, means 100 partly on the vehicle and partly along the track for causing voltage variations in said coil under dangerous traffic conditions, train control means on the vehicle, and an audion responsive to said induced voltage for governing the operation of said train control means.

9. Impulse transmitting means for automatic train control systems comprising, a car-carried circuit and cooperating means 110 on the trackway effective to produce an induced voltage in a coil on the car which varies in strength in accordance with the speed of the car, a thermionic relay influenced by said induced voltage, and electro-responsive means on the car controlled by said relay.

10. Impulse transmitting means for automatic train control systems responsive to the speed of a vehicle comprising, means 110 acting to produce an induced voltage in a circuit on a car which varies in accordance with the speed of the car at predetermined control points, and means including a thermionic relay for detecting the variations in 125 said induced voltage.

11. In an automatic train control system, impulse transmitting means comprising a

- car-carried element constituting a partial magnetic circuit, a trackway element adapted when in the active or stopping condition to complete the partial magnetic circuit on the car, a source of magneto-motive force for said magnetic circuit, a coil on the car included in said magnetic circuit, an audion having its grid circuit connected to said coil, and an electro-responsive device connected in the plate circuit of the audion. 12. In an automatic train control system, impulse transmitting means comprising a car-carried yoke provided with a field coil and a secondary coil, a trackway element adapted when in the active or stopping condition to complete the partial magnetic circuit of the car-carried yoke, an audion having its filament connected in circuit with the field coil and its grid circuit connected to the secondary coil, and a control relay connected in the plate circuit of the audion. 13. In an automatic train control system, impulse transmitting means comprising a trackway element including a magnetic yoke and coils, traffic controlled means for controlling the circuit of the coils of said trackway element, a car-carried element comprising a magnetic yoke and having a field coil and a secondary coil, a source of magneto-motive force for the car-carried yoke, an audion having its filament connected in circuit with the field coil and its grid connected in circuit with the secondary coil, a control relay included in the plate circuit of the audion, and means on the vehicle for supplying energy to the circuits of the audion. 14. In an automatic train control system for railway vehicles, a normally energized electro-responsive device on the vehicle, adapted when deenergized to cause automatic control of the vehicle, an audion controlling said device, means on the vehicle for normally maintaining a uni-directional potential on the grid of said audion and thereby maintaining energization of said device, and traffic controlled means for changing the amplitude of said grid potential to cause deenergization of said device. 15. In an automatic train control system for railway vehicles, normally energized train control apparatus on the vehicle, and means for causing deenergization of said apparatus at control points along the track comprising an audion, the grid circuit of which is maintained energized by a uni-directional potential and car-carried and trackway elements cooperating inductively through an intervening air-gap. 16. Car equipment for automatic train control systems comprising an audion, a relay connected in the plate circuit of the audion, a car-carried circuit for normally maintaining a uni-directional potential on the grid of the audion, and traffic controlled trackway means acting to reduce said grid potential and thereby causing deenergization of said relay. 17. In an automatic train control system, train control apparatus on a vehicle including a thermionic relay, an input circuit for said relay including a source of uni-directional potential, and means partly on the track and partly on the vehicle for influencing said input circuit at selected control points along the track. 18. In an automatic train control system, impulse transmitting means comprising an audion on a vehicle, a circuit on the vehicle including a source of current for heating the filament of the audion, a coil in said circuit, and means for producing voltage variations in said coil at control points along said track. 19. In an automatic train control system, brake control apparatus on a car, control means on the car for initiating operation of said apparatus and comprising a group of normally energized devices and circuits, said control means including a control relay of the tractive type and a vacuum tube amplifier said control relay being included in the plate circuit of said amplifier, a circuit and a source of electricity constantly applying a uni-directional potential to the grid of said amplifier, and means comprising cooperating car-carried and track elements adapted to act intermittently at selected control points along the track for influencing said circuit only under dangerous traffic conditions to vary the potential applied to the grid of the amplifier and thereby cause effective deenergization of the control relay and operation of said apparatus. 20. In an automatic train control system, impulse transmitting means comprising track elements acting as a mass of iron when in the active stopping condition, and car equipment including an electro-responsive device of the audion type having a grid circuit normally energized from a source of uni-directional potential, said circuit being influenced by said track elements in the active condition. 21. Impulse transmitting means for automatic train control systems comprising a partial magnetic circuit on a vehicle, trackway means for changing the reluctance of said circuit, a coil associated with said circuit, and means including a thermionic relay of the audion type having a grid circuit normally energized by a uni-directional potential, said grid circuit being responsive to voltage variations in said coil. 22. Impulse transmitting means for automatic train control systems comprising a partial magnetic circuit on a vehicle, trackway means for intermittently influencing said circuit, and means including a thermionic relay of the audion type having a grid circuit normally energized by a uni-directional potential. 70 75 80 85 90 95 100 105 110 115 120 125 130

directional potential, said grid circuit being responsive to flux variations in said magnetic circuit.

23. Car equipment for automatic train

5 control systems comprising an energized partial magnetic circuit, a coil associated with said circuit, an electro-responsive device of the audion type having its input circuit normally energized by a uni-directional 10 potential and connected to said coil, and train control means governed by the output circuit of said device.

15 24. In an automatic train control system, brake control apparatus on a vehicle, amplifying means for governing said apparatus and having an input circuit, a source of current for constantly energizing said input circuit and traffic controlled track elements at 20 intervals along the track for producing induced voltage in said input circuit to neutralize partially the voltage of said source and cause actuation of the brake control apparatus.

25 25. In a train control system, brake control apparatus on a vehicle, control means therefor including an amplifier, and car carried and track elements cooperating through an intervening air gap for governing said control means, said track elements each comprising 30 a non-magnetized mass of iron and a winding in magnetic circuit therewith, said winding being automatically placed on open circuit under dangerous traffic conditions and being included in a closed deenergized 35 circuit of low resistance under clear traffic conditions.

40 26. In a train control system, brake control apparatus on a vehicle, control means therefor including an amplifier and a normally closed circuit energized with uni-directional voltage, and means partly on the vehicle and partly on the track and including cooperating partial magnetic circuits for 45 producing voltage changes in said circuit in partial opposition to its energizing voltage and thereby causing operation of the brake control apparatus.

45 27. In a train control system, the combination with a car carried element constituting a partial magnetic circuit, means for maintaining in said magnetic circuit a uni-directional flux, and trackway means for varying the reluctance of said circuit, of train control apparatus on the car including amplifying 55 means and responsive to flux variations in said partial magnetic circuit.

60 28. Car apparatus comprising a magnetic core, a coil thereon, a circuit including said coil and a source of direct current, train control apparatus, and amplifying means responsive to potential changes in said circuit for governing said apparatus.

65 29. A train control system comprising, brake governing apparatus on a vehicle, an audion controlling said apparatus, a circuit

including a coil and a source of electrical energy for normally maintaining a uni-directional potential on the grid of the audion, and means partly on the vehicle and partly on the track for producing voltage changes 10 in said coil.

30. In a train control system in which controlling influences are communicated from the trackway to moving vehicles by electromagnetic induction, car apparatus comprising 75 a magnetic core and a coil thereon, a normally closed control circuit including said coil and a source of current, brake control means governed by voltage changes in said circuit, trackway means cooperating 80 with said core and coil to produce changes of flux therein and induce opposing voltage in said coil and control circuit, and other means responsive to the flux produced by the coil for checking the integrity of the control 85 circuit.

31. In a train control system in which controlling influences are communicated from the trackway to moving vehicles by electromagnetic induction, train control apparatus 90 and governing means therefor comprising a normally energized circuit and amplifying means, and biased circuit controlling means independent of said governing means and operated by flux produced by the flow of 95 current in said circuit for detecting interruption of said circuit.

32. In a train control system in which controlling influences are communicated from the trackway to moving vehicles by electromagnetic induction, a control relay, and an audion governing said relay and having uni-directional potential normally maintained on its grid by a source of current on the vehicle.

40 33. In a train control system in which controlling influences are communicated from the trackway to moving vehicles by electromagnetic induction, in combination with track elements constituting an inert mass of iron when in the active stopping 105 condition, a coil normally energized by a uni-directional potential in which potential changes are produced during the passage of the vehicle by said track elements, a relay of the tractive type normally energized by 110 direct current, and means for amplifying such potential changes and utilizing them to cause effective deenergization of said relay.

34. In a train control system, the combination with a control relay on a vehicle, a coil 115 on the vehicle in which potential changes are produced by trackway means, circuit connections between the coil and control relay, and means independent of said control relay and its circuit connections and responsive to the 120 flux produced by the coil for detecting failure of said circuit connections.

35. In a train control system of the type described in which governing influences are 125 communicated from the trackway to the 130

- moving vehicle through an intervening air-gap by the transfer of magnetic flux, the combination with brake control apparatus on the vehicle, of a normally energized relay 5 of the tractive type maintaining said apparatus inactive, a track element having an iron core and a winding magnetically associated with said core, track circuit controlled means for placing said winding on open circuit under dangerous traffic conditions and 10 for including said winding in a closed de-energized circuit under safe traffic conditions, a car-carried core with a coil thereon adapted to cooperate with said track element, an amplifier of the vacuum tube type 15 electrically connecting said coil and said relay, and a source of direct current maintaining said coil and amplifier energized.
36. Car carried impulse receiving means 20 for train control systems comprising, an audion, brake control apparatus normally maintained inactive by potential on the grid of said audion, and means adapted to be influenced from the trackway for varying the 25 grid potential of the audion, said means including an energized coil connected in series with the filament of the audion.
37. In a system for controlling relays on 30 railway vehicles inductively by exchange of flux between the vehicle and the trackway, means partly on the vehicle and partly on the track constituting two cooperating partial magnetic circuits, a source of magneto-motive-force for the completed magnetic 35 circuit formed by said partial circuits, traffic controlled means on the track for opposing the passage of flux through said completed magnetic circuit, a receiving coil on the vehicle responsive to a change in the flux 40 through the partial circuit on the vehicle, and an audion connected to said receiving coil and controlling the train control relay.
38. Car-carried apparatus for automatic 45 train control systems comprising, a car element of magnetic material having a normally energized field coil and a secondary coil thereon, means connected to said secondary coil for detecting sudden changes of flux therethrough, and other means for detecting 50 a failure of flux through said secondary coil.
39. In a system for controlling the brakes 55 of railway vehicles by influences transmitted inductively from the trackway to car-carried devices comprising, a car element including a normally energized field coil and a secondary coil, a thermionic device having a filament, a grid and a plate, a circuit for said filament including said field coil and a source of energy, a circuit for said grid including said secondary coil, and a circuit for 60 said plate including a source of energy, the various constants of said thermionic device being so adjusted that either a decrease of current in said filament or a decrease of potential on said grid will cause a decrease of current in said plate circuit.
40. Car-carried apparatus for train control systems comprising, a core of magnetic material having a field coil and a secondary coil thereon, said field coil being connected in a circuit including a source of uni-directional potential and energized to produce enough flux to transmit a control influence to the secondary coil when passing over an active trackway element, normally energized 70 brake control means which if deenergized will apply the brakes; and means for de-energizing said brake control device when the current in the energizing circuit for the field coil decreases to a predetermined extent, or when a sudden change of flux through the secondary coil takes place, and other means for deenergizing said brake control device when the flux through said secondary coil falls to a predetermined value.
41. Car-carried apparatus for automatic 75 train control systems comprising, a yoke of magnetic material having a downwardly extending leg normally magnetized by uni-directional magneto-motive-force, a coil on 80 said leg for detecting a rapid change of flux therethrough, and flux responsive means associated with said yoke for detecting the failure of such flux.
42. Influence transmitting means for 85 transmitting control influences from the trackway to a moving vehicle for train control systems comprising, an audion provided with the usual filament, plate and grid, a plate circuit for the audion including a 90 source of energy and a normally energized electro-responsive device, and means partly along the track and partly on the vehicle for simultaneously varying the temperature of the filament and the potential impressed 95 upon the grid of said audion, whereby a cumulative influence will be transmitted to said electro-responsive device.
43. In an automatic train control system, the combination of brake control apparatus 100 on a vehicle and of control means upon the vehicle for initiating operation of said apparatus comprising, a core of magnetic material, a field coil for producing a magneto-motive-force in said core, a secondary coil 105 on said core, and means including an audion cumulatively responsive to a decrease of current in said field coil and to a change of flux through said secondary coil for initiating 110 operation of said brake control apparatus.
- 115
